UNITED STATES PATENT OFFICE

2,549,119

CHAIR STRUCTURE

Walter E. Nordmark, Grand Rapids, Mich., assignor to American Seating Company, Grand Rapids, Mich., a corporation of New Jersey

Application February 21, 1947, Serial No. 729,987

1 Claim. (Cl. 155—160)

1

The present invention relates to chair structures and more particularly to chairs of the reclining type adapted for installation in motor buses, railway coaches, airplanes and other vehicles.

The primary objects of the invention are to provide an improved chair of the reclining type, i. e. a chair in which the back may be tilted rearwardly beyond its normal, slightly rearwardly tilted position thus to provide a more restful position for the occupant of the chair; to provide such a chair having improved, manually controlled, back-supporting mechanism by means of which the angular tilt of the back may be selectively adjusted by the chair occupant; to provide such adjustable back-supporting mechanism which is particularly sturdy in construction; to provide such a chair structure in which is incorporated an improved, adjustable foot rest for the use of an occupant of a reclining chair installed rearwardly thereof; and in general to provide such an improved chair structure which is efficient in operation, reasonably economical in manufacture, and attractive in appearance.

The accompanying drawings illustrate a preferred embodiment of the invention, and the various views in these drawings are described as follows:

Figure 1 is a front perspective view of a two-passenger reclining chair adapted for installation in a motor vehicle or the like;

Figure 2 is a rear perspective view of the same;

Figure 3 is a fragmentary view of the supporting frame of the chair structure, the upholstered seat and back cushions being omitted in this view to reveal the back-supporting mechanism and the foot rests and mounting means therefor;

Figure 4 is an enlarged, inside elevational view of the manually operable, adjustable back-supporting mechanism and the adjacent foot rest mounting means, certain parts of the structure being shown in this view in section taken on line 4—4 of Figure 3;

Figure 5 is a fragmentary, sectional view of parts shown in Figure 4, the section being taken on line 5—5 of Figure 4;

Figure 6 is a fragmentary, sectional view of parts thereof taken on lines 6—6 of Figures 4 and 5;

Figure 7 is a fragmentary, rear elevational view of a foot rest and the mounting means therefor; and

Figure 8 is a view partly in side elevation and partly in section taken on line 8—8 of Figure 3

2

showing the back tilting mechanism of the chair structure.

Referring now in detail to these drawings, the chair structure there shown generally comprises a horizontal supporting frame of metal tubing, having a front rail 1, end rails 2, 3, a rear rail 4 and a middle rail 5 parallel to the end rails 2, 3. This horizontal supporting frame is mounted in a vehicle as by means of an angle bar 6 secured to the vehicle's side wall by bolts 7 and to an end rail 2 of the frame by means of brackets 8, 9 welded to the frame and secured by bolts 10, 11 to the angle bar 6. The aisle side of the supporting frame is mounted by any conventional means on an end pedestal or standard 12, and a depending rear leg 13 gives additional support to the frame.

The supporting frame as above described is adapted to support seats for two persons, said seats being here shown in the form of an integral seat cushion 14 of sufficient width for two persons and extending from end to end of the supporting frame. The chair backs 15 are of individual width, a separate back being provided for each chair occupant and the backs being independently adjustable as to pitch. Each chair back 15 comprises a rectangular, tubular metal frame 16 to which is secured as by brackets 17 and bolts or rivets 18 a back panel 19 of plywood or the like which may if desired be covered with an upholstery material. Padding is applied to the front of each back panel 19 and an upholstery covering 20 is disposed over the padding, drawn rearwardly at the edges, and secured to the back panel 19 in any conventional manner. The tubular metal frames 16 of the chair backs, and also the upper portions of the back-supporting mechanisms hereinafter described, are thus concealed beneath the upholstery coverings 20.

Each chair back is swingably mounted on and between a pair of horizontally spaced back-supporting uprights 21 and 22, the uprights 21 being secured as by welding to the end rails 2, 3, respectively of the supporting frame and having the adjustable back-supporting mechanisms mounted thereon, and the uprights 22 being secured as by welding to opposite sides of the middle rail 5 of the supporting frame. Brackets 23 pivotally connected at 24 to the uprights 21 and welded to the tubular back frames 16 secure the outer sides of said frames to the uprights 21, while brackets 25 pivotally connected at 26 to the uprights 22 and welded to the frames 16 secure the inner sides of said frames to the

uprights 22. The chair backs are thus independently mounted for tilting movement about horizontal axes near the bottoms of said backs. Forward tilting movement is limited by contact of the frames 16 with stops 27 on the uprights 21, in which forwardmost position of the back it is only slightly rearwardly inclined. Rearward tilting movement of the back is limited by contact of the lower portions of the back frames 16 with the rearward edges of the uprights 21 and 22.

Means are provided for normally urging each of the chair backs 15 toward its forwardmost position, comprising a cylinder 28 pivotally connected near its upper end to a bracket 29 secured as by welding to the inner vertical portion of the adjacent tubular back frame 16. A plunger 30 has an upper head 31 (see Figure 8) reciprocally disposed in each cylinder 28 and has its lowermost end turnably bearing against the adjacent upright 22, each upright 22 being provided with a laterally extending lug 32 having a hemispherical socket 33 for turnably receiving the hemispherical lower extremity of the adjacent plunger 30. Preferably each plunger 30 extends upwardly through its head 31 and has a bearing 34 in the upper end 35 of its cylinder 28. A coiled compression spring 36 is disposed within each cylinder 28 between the upper end of said cylinder and the head of the plunger therein. The springs 36 are sufficiently strong to normally urge the chair backs 15 to their forwardmost positions, but are yieldable under backward pressure of the chair occupants.

Mechanisms for selectively adjustably securing the backs 15 in tilted positions intermediate their forwardmost and rearwardmost positions are mounted adjacent the outer ends of the chair structure. A sector 37, having forwardly and downwardly extending teeth 38 arranged concentrically about the pivotal connection of the adjacent bracket 23 to its upright 21, is secured as by welding to the outer vertical portion of the adjacent tubular back frame 16. The teeth 38 of each sector 37 are adapted to be engaged in various tilted positions of the adjacent back 15 by the upper end of a detent member 39 slidably disposed in a slide bearing 40 formed by bending the upper rearward edge of the adjacent upright 21 in an inwardly, rearwardly and then outwardly direction. A bell crank 41 pivotally mounted at 42 on said upright 21 has one arm 43 thereof pivotally connected to the lower end of the detent member 39 and the other arm 44 thereof pivotally connected to the upper end of a link 45. The lower end of the link 45 has a pivotal connection 46 with the rearward end of an arm 47 rigidly connected at its forward end to a stud 48 pivotally mounted on the upright 21. The pivotal connection 46 extends through an elongated slot 49 in the upright 21, which slot permits limited movement of the connection.

A manually operable control lever 50 is also fixedly connected to the stud 28 and the arm 47 is thus movable with the control lever 50. It will be seen that when the forward end of the control lever 50, which is accessible to the chair occupant, is depressed, arm 47 moves link 45 upwardly thus turning bell crank 41 in a counter-clockwise direction as viewed in Figures 3 and 4, and the bell crank 41 in turn moves the detent member 39 forwardly-downwardly to disengage said detent member from the teeth 38 of the sector 37, thus freeing the back so that it may be moved forwardly and rearwardly by the chair occupant until the back is positioned to suit

the occupant, whereupon the control lever 50 may be released and the detent member is returned to its position of engagement with the sector 37 by the action of a tension spring 51 connected to the upright 21 and to the upper arm 43 of the bell crank 41. The chair back is thus secured in selected, angularly adjusted position.

Adjustable foot rests 52 are incorporated in the chair structure for the use of the occupants of the chair structure installed in the rear of that shown. The mounting means for each foot rest comprises spaced depending mounting plates 53 secured to the adjacent end rail 2 and middle rail 5 respectively. Hanger brackets 54 are pivotally connected at 55 to each pair of mounting plates 53, and a foot rest 52 of cross-sectionally elliptical tubular formation is pivotally mounted on a tube 56 rigidly connected at its opposite ends to the hanger brackets 54.

The hanger brackets 54 of each pair have companion series of ratchet teeth 57 (see Figure 4) arranged concentrically with the pivotal connections of said hanger brackets to the mounting plates 53, and have semicircular voids 58 and 59 at the opposite ends of each series of ratchet teeth. Companion pawls 60 are pivotally mounted at 61 on the mounting plates 53 of each pair, said pawls being adapted to engage in a companion pair of ratchet teeth 57 on the adjacent hanger brackets to maintain said brackets and the foot rest in selected elevated position. A tension spring 62 is connected to each pawl 60 and to its adjacent mounting plate 53 for maintaining the pawl in bearing engagement with the adjacent hanger bracket. It will be seen that as the foot rest is moved upwardly, the angle of the pawls' bearing against the hanger brackets is such that the pawls are in position to engage the ratchet teeth and maintain the foot rest in selected elevated position. When the foot rest reaches an extreme position of elevation, the pawls drop into the voids 59 and subsequent lowering movement of the foot rest reverses the angle at which the pawls bear against the hanger brackets. Thus the pawls do not engage in the ratchet teeth during lowering movement of the foot rest. When the foot rest reaches its extreme lowered position, the pawls fall into the voids 58 of the hanger brackets and are thus free to resume their angle of engagement with the ratchet teeth during subsequent raising movement of the foot rests.

It will thus be seen that an improved chair of the reclining type has been provided which is of sturdy construction and which is adjustable to insure maximum comfort, and while but one specific embodiment of the invention has been herein shown and described, it will be understood that modifications may be conceived which fall within the scope of the appended claim.

I claim:

In a chair structure: a supporting frame having a pair of horizontally spaced back-supporting uprights; a back pivotally connected to said uprights for tilting movement about a horizontal axis near the bottom of the back; spring means associated with one of said uprights and with the adjacent side of the back for normally urging the back forwardly, said spring means comprising a downwardly opening cylinder mounted on the back above the said upright, a plunger having an upper head reciprocally disposed in the cylinder and a lower end bearing against said upright, and a compression spring confined between the plunger's head and the upper end

of the cylinder; stop means on the frame for limiting the forward movement of the back to a forwardmost position in which the back is only slightly rearwardly tilted; a toothed sector fixedly mounted on the back and swingable therewith; a slide bearing fixedly mounted on the frame with an end thereof adjacent the toothed edge of the sector; a detent member slidably disposed in the slide bearing and having an end thereof adapted to engage and disengage the sector's toothed edge in oppositely moved positions of the back; and operating means associated with the detent member and accessible to the chair occupant for sliding said member to and from its position of engagement with the sector's toothed edge. 18
